TAP STRUCTURE

John S. Bartek, Rochester, N. Y., assignor to
 Consolidated Machine Tool Corporation, Rochester, N. Y., a corporation of Delaware

Application July 30, 1936, Serial No. 93,440

5 Claims. (Cl. 10—145)

My invention relates to a tap structure of the type in which the chasers are automatically retracted at the end of a threading operation, and has for its object to afford an improved simple and practical arrangement for adjusting the parts, to vary the position of the chasers when in operative position, in accord with the diameter of the work.

A further purpose of the invention is to provide an economical construction in which an adjustable locking means is provided for holding the chasers in variable position when in operative relation, in conjunction with a removable nose or frame attachable to the body of the tap and carrying the chaser assembly, whereby different chaser assemblies may be employed on the same body.

Another object of the invention is to afford an adjustable locking assembly that is located in one side of the body of the tap so that the locking member can cooperate with the actuating block by a lateral movement without interfering with the connection between the actuating block and the chaser assembly, thus contributing to produce a more simple and efficient design.

To these and other ends, the invention consists in the construction and combination of parts that will appear clearly from the following description when read in conjunction with the accompanying drawing, the novel features being pointed out in the claims following the specification.

In the drawing:

Fig. 1 is a longitudinal central sectional view of a tap, showing one embodiment of the invention, with the chasers in operative position;

Fig. 2 is a transverse sectional view on the line 2—2 of Fig. 1;

Fig. 3 is a plan view of the locking member and its housing removed from the body, and

Fig. 4 is a sectional view of the sleeve and adjustably connected trip plate.

Referring more particularly to the drawing, in which like reference characters refer to the same parts throughout the several views, 1 designates the body of the tap having a central longitudinal opening within which is slidably mounted an actuating block 2 to which is connected a rod 3 extending into a chamber in the extension 4 of the body. The rod 3 has a head 5 against which seats a spring 6 that controls the actuating block and moves the latter to withdraw the chasers from engagement with the work to inoperative position when the threading operation is completed.

The chasers are designated at 7, and are mounted for lateral movement in a nose or frame 8 which is removably attached to the body by the bolts 9, the chasers being moved laterally by cam members 10 operatively connected thereto and carried by a post 11 which is removably associated with the actuating block 2.

Slidably mounted on the body 1 is a sleeve 12 to which are adjustably connected the arms 13, while 14 is the trip plate attached to the outer end of said arms 13 and operating, when engaged by the work or by a stationary part at the completion of the threading operation, to force the sleeve 12 endwise on the body and effect release of the chasers in the manner that will appear presently. 15 is a hand lever pivoted at 16 to the body 1 and having its inner end engageable with a pin 17 extending laterally and carried by the sleeve 12. The inner end of the hand lever 15, and the pin 17, extend through an opening in the actuating block 2, and the hand lever 15 is operable to move the actuating block 2 and the chasers to operative position, preparatory to the threading operation.

In order to lock the actuating block 2 and chasers in operative position, a recess is provided in the body at one side of the central opening, and in said recess is adjustably mounted a housing 18. In said housing 18 is pivoted a cam lever 19 having a nose 20 which engages a locking member or block 21 that is slidable laterally in said housing 18 and adapted to engage a shoulder on the actuating block 2. 22 is a spring seated in a recess in the cam lever 19 and engaging against a surface of the body, to hold the cam lever and the locking member normally in locking position, as shown in Fig. 1. The cam lever 19 has a cam surface 23 which extends into an opening 23^a of the sleeve 12. When the sleeve 12 is moved endwise, by engagement of the trip plate at the end of the threading operation, it moves the cam 23 of the cam lever inwardly and the nose 20 outwardly, thereby withdrawing the locking member 21 from engagement with the actuating block 2 and releasing the same, which is thereupon retracted by the spring 6, and the chasers thus move inwardly away from the work.

It is desirable to provide means for adjusting the operative position of the chasers, and this is accomplished by varying the position of the locking member 21 endwise of the body. To accomplish this, the housing 18 has a threaded opening which is engaged by a threaded adjusting screw 24 which extends through an opening in the body and has a head 25 abutting against the body.

By turning the adjusting screw 24, the housing 18 can be moved endwise of the body, and in this fashion the endwise location of the locking member 21 can be adjusted, to determine the extent 5 of outward movement of the chasers.

In order to hold the adjusting screw 24 in its adjusted position, and prevent accidental displacement, the head 25 is provided with serrations around the side thereof, and a spring-controlled plunger 26 is mounted in an opening in the body and movable transversely thereof to engage said serrations on the side of the head, as shown in Fig. 2. For the purpose of permitting access to the adjusting screw 24 to change the 10 position of the locking member, an opening 27 is provided in the nose or frame 8, through which a screw driver can be inserted to turn the adjusting screw against the resistance of the spring-actuated friction locking plunger 26.

The parts are shown in operative position in Fig. 1, having been restored to this position by manual operation of the lever 15 and retained by the locking member 21. After the threading operation is completed, the trip plate 14 is engaged as usual in this type of mechanism, causing an endwise movement of the sleeve 12 which thereupon engages and rocks the cam lever 19 and moves the locking member 21 outwardly to release the actuating block 2. The latter is retracted by the spring 6, causing corresponding endwise movement of the post 11 and thus retracting the chasers. The parts are restored to operative position by manipulating the hand lever 15, as already described.

While the invention has been set forth with reference to a particular construction, it is not confined to the details herein shown, and this application is intended to cover such modifications or changes as may come within the pur- 40 poses of the improvement or the scope of the following claims.

I claim:

1. In a tap structure, the combination with a body having a central longitudinal opening, 45 of a spring-controlled actuating block movable endwise of the body in said opening, chasers operatively connected to the actuating block, a lever pivoted to the body for operating said actuating block, the body having a recess at one side of said central opening, a housing located in said recess, a locking member supported in said housing and movable laterally of the body into engagement with the actuating block, a cam lever pivoted in said housing and connected to 50 said locking member, and means for adjusting the housing endwise in said recess.

2. In a tap structure, the combination with a body having a central longitudinal opening, of a spring-controlled actuating block movable end- 60 wise of the body in said opening, chasers operatively connected to the actuating block, a lever pivoted to the body for operating said actuating block, the body having a recess at one side of said central opening, a housing located in said 65 recess, a locking member supported in said hous-

ing and movable laterally of the body into engagement with the actuating block, a cam lever pivoted in said housing and connected to said locking member, an adjusting member supported by the body and having threaded engagement with said housing, a head on said adjusting member having serrations on its side, and a spring-actuated plunger movable laterally in the body and engaging said serrations on the head. 5

3. In a tap structure, the combination with a body having a central longitudinal opening, of a spring-controlled actuating block movable endwise of the body in said opening, chasers operatively connected to the actuating block, a lever pivoted to the body for operating said actuating block, the body having a recess at one side of said central opening, a housing located in said recess, a locking member supported in said housing and movable laterally of the body into engagement with the actuating block, a cam lever pivoted in 10 said housing and connected to said locking member, an adjusting member supported by the body and having threaded engagement with said housing, a head on said adjusting member having serrations on its side, a spring-actuated plunger movable laterally in the body and engaging said serrations on the head, and a chaser-supporting nose removably attached to the body, said nose having an opening permitting access to said adjusting member. 20

4. In a tap structure, the combination with a body having a central longitudinal opening, of a spring-controlled actuating block movable endwise of the body in said opening, chasers operatively connected to the actuating block, a lever pivoted to the body for operating said actuating block, the body having a recess at one side of said central opening, a housing located in said recess, a locking member supported in said housing and movable laterally of the body into engagement with the actuating block, operating means in said housing connected to said locking member, means for adjusting the housing endwise in said recess, and a sleeve slidable on the body and controlling 35 said operating means in the housing. 40

5. In a tap structure, the combination with a body having a central longitudinal opening, of a spring-controlled actuating block movable endwise of the body in said opening, chasers operatively connected to the actuating block, a lever pivoted to the body for operating said actuating block, the body having a recess at one side of said central opening, a housing located in said recess, a locking member supported in said housing and movable laterally of the body into engagement 55 with the actuating block, a cam lever pivoted in said housing and having one end connected to said locking member, a spring located between the other end of said cam lever and the wall of said recess in the body, means for adjusting the housing in said recess, and a sleeve slidable on the body and cooperating with the outer end of said cam lever. 60
